[57] **CLAIM**

The ornamental design for a hand-held light for personal protection, as shown and described.

DESCRIPTION

FIG. 1 is a front, top and side perspective view of the hand-held light for personal protection showing our new design;

FIG. 2 is a side elevational view thereof;

FIG. 3 is a side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The personal protection light is used for blinding an attacker.

FIG. 1
